UNITED STATES PATENT OFFICE.

GEORGE P. TILTON, OF NEWBURYPORT, MASSACHUSETTS.

DESIGN FOR A SPOON, FORK, OR SIMILAR ARTICLE.

SPECIFICATION forming part of Design No. 28,924, dated June 28, 1898.

Application filed May 20, 1898. Serial No. 681,258. Term of patent 7 years.

To all whom it may concern:

Be it known that I, GEORGE P. TILTON, a citizen of the United States, residing at Newburyport, in the county of Essex and State of 5 Massachusetts, have invented and produced a new and original Design for Spoons, &c.; and I do declare the following to be a full, clear, and exact description of the same, reference being had to the accompanying drawings, forming a part of this specification, in which—

Figure 1 represents the obverse of a spoon which embodies my new design. Fig. 2 represents the reverse thereof, and Fig. 3 is a cross-section of Fig. 1 on line 3 3.

The leading feature of my design consists in the adaptation of certain novel and ornamental elements in combination to the form of a handle, with consequent outline, as shown.

The ornamentation shown is as follows: 5 The obverse presents a spoon-handle of columnar character having at its base or point of juncture with the spoon-bowl a claw-like arrangement and surmounted with a capital bearing a basket of flowers and dependent festoon.

The contributive and essential details are a mainly-convex surface *a a a*, (best shown in Fig. 3,) having tapering longitudinal surfaces *a'*, alternating with similarly-tapering flutes or grooves *a²*; a floral spray in relief, *b*, on the surface *a* at the point of greatest convergence of *a' a²*; an arrangement of talons or claw-like members *c c*, partly coincident with the outline of the handle and seeming to engage the bowl, which is apparently continued upward by the member *d*, having branching subdivisions *d' d²*, the upper portion *d'* covering the union of talons *c c* with surface *a*; a composite capital *e*, from the volutes *e' e'* of which depends a floral festoon *f*, the outer ends disengaged from the column *a e* by the openings *g g* and the intermediate portion in relief on the surface *a a*; a basket *h*, placed as if resting on capital *e* and containing flowers 5 *i i i*, which form the upper or free end of the handle.

The reverse presents a spoon-handle having a slightly-convex surface connected at its base or point of juncture with the spoon-bowl by a claw-like arrangement and surmounted by 50 a shell form flanked by scrolls and surmounted by floral forms.

On the convex surface appear the borders *j j* of raised flat longitudinal surfaces of equal breadth, separated by a correspondingly-rang- 55 ing groove, which borders originate in the talons *k k*, which are the complement of talons *c c*, Fig. 1, and terminate in the scrolls *l l* and rosettes *m m*, from which issue the foliated branches *n n*, returning on and inter- 60 rupting the borders *j j*. The borders *j j* are further interrupted in the lower and narrow portion of the handle by the plate forms *o o* in combination with leaves *p p*.

In the crowning group shell form *q* has lineal 65 border emanating from borders *j j*, with waved band *r* beneath and above a plurality of floral forms *s s s*, which complete the border of reverse and coincide with outline formed by members *i i i*, Fig. 1. 70

The bowl is ornamented in relief, having at its inner end, near the point of juncture of the handle, the basket *t*, containing flowers *u* and from which depends the floral festoon *v*.

Having thus described my invention, I 75 claim—

1. In the design for a spoon, fork or similar article, the obverse as herein shown and described.
2. In the design for a spoon, fork or similar article, the reverse as herein shown and described.
3. The design for a spoon, fork, or similar article, as herein shown and described.

In testimony whereof I affix my signature 85 in the presence of two witnesses.

GEORGE P. TILTON.

Witnesses:

NATHANIEL N. JONES,
A. E. BROWN.
